UNITED STATES PATENT OFFICE.

FRANK L. MORGAN, OF CINCINNATI, OHIO, ASSIGNOR TO UNDERWOOD TYPEWRITER COMPANY, OF NEW YORK, N. Y., A CORPORATION OF DELAWARE.

TYPE-WRITING MACHINE.

1,194,655.

Specification of Letters Patent. Patented Aug. 15, 1916.

Application filed December 22, 1914. Serial No. 878,483.

To all whom it may concern:

Be it known that I, FRANK L. MORGAN, a citizen of the United States, residing in Cincinnati, in the county of Hamilton and State of Ohio, have invented certain new and useful Improvements in Type-Writing Machines, of which the following is a specification.

My invention relates to front work-sheet 10 guiding and gaging means for front-strike writing machines, particularly those in which a roller platen has a case-shifting movement.

The invention provides means which 15 serves as a gage shiftable with the platen to indicate the position of the writing line on the work-sheet while the platen is in both lower and upper case positions; provides a platen scale; and forms a work-piece holder 20 adapted to hold a sheet or work-piece in position on the platen after the lower edge of the sheet has passed beyond the usual platen feed rolls, thereby enabling the writing to be carried practically to the bottom of the 25 sheet.

In carrying out the invention, swinging plates or wings may be mounted on the machine frame or type-bar segment at opposite sides of the printing point, and caused 30 to bear with a moderate yielding pressure against the platen or work-piece thereon, along the writing line and serving as gages to indicate the position of the bottom edge of the writing line; said plates preferably 35 provided with scale graduations at letter-space intervals along the writing line. To enable the gages to shift up and down with the platen, they have an up and down sliding connection with their supports. The 40 shifting movement of the gages is effected by a rod mounted on the platen frame and extending longitudinally of the platen, and having a horizontal sliding connection with said gages which permits the gages to re- 45 main stationary during the letter feed of the platen, but forms a positive means for shifting the gages up and down with the platen during the case-shifting movements of the latter, so that the gages maintain a 50 constant relation to the writing line, and accurately indicate the latter in both upper and lower case positions. The scale plates or gages constantly bear against the platen as they shift therewith, and thus serve to 55 hold a work-sheet after the bottom edge of

the latter has passed beyond the platen feed rolls, and prevent the work-sheet from becoming displaced during the case-shifting movements of the platen so that the writing may be carried close to the bottom of the 60 sheet. Said scale plates further serve for holding cards, envelops and other small work-pieces on the platen. As the said plates bear against the face of the work-piece along the printing line, the usual tendency of a stiff card, or other small work-piece to spring away from the platen along the printing line is overcome, and the work-piece held firmly against the platen at the 65 printing point, enabling clear type impressions to be made.

In some machines the rising scale plates, if shiftable to upper-case position throughout the entire range of the carriage travel, would have to be made short to prevent 70 them from striking the carriage frame when the carriage is near either limit of its travel, or the construction of the machine might be such as to preclude the use of rising scale plates with the carriage near its limits of 75 travel. The present invention provides means whereby such interference may be avoided, and the scale plates in practice materially lengthened, thereby increasing their 80 effectiveness and usefulness. To this end, 85 means is provided for preventing each scale plate from being shifted up or held up with the platen when the adjacent end of the carriage has been brought within striking range 90 of the scale plate. For this purpose, the 95 supporting rod on the carriage which shifts the scale plates up and down, is made of such length that each scale plate will run off the rod when the end of the carriage approaches the scale plate, allowing the latter 100 to drop if in upper-case position, and preventing it from rising if the platen is shifted up while the carriage end is within range 105 of the scale plate. To further assist in this operation, cams may be provided on the carriage, one adjacent each end of said rod, to swing the scale plates off the rod. Said 110 cams further serve to hold the scale plates away from the platen, so that when a work-sheet is shifted up and down with the platen while the bottom edge of the sheet is near the printing line, the scale plate held away from the platen will not catch on the corner of the work-sheet as the platen is shifted up and down. Said cams also protect the usual 115

front platen feed rolls from being rubbed by the scale plates as the feed rolls pass the scale plates during the longitudinal movement of the platen.

8 Other features and advantages will hereinafter appear.

In the accompanying drawings, Figure 1 is an elevation showing the platen and rising scale plates in upper-case position, the carriage being at the center of its travel. Fig. 2 is a similar view with the carriage near the starting point in which position the left-hand rising scale plate is released from its supporting rod and moved down to lower case position to prevent interference with the carriage frame. Fig. 3 is a rear perspective view showing the rising scale plates, one of said plates being in upper-case position and the other released and held down in normal or lower-case position. Fig. 4 is a sectional end elevation showing the platen in upper case position and a rising scale plate carried off its supporting rod, and dropped down to lower case position. Fig. 5 is a fragmentary plan view showing the platen in upper case position and approaching the end of its travel to the right. Fig. 6 is a sectional elevation showing the platen and a rising scale plate in upper-case position. Fig. 7 is a sectional elevation view of an Underwood typewriting machine with the present invention applied thereto, the platen and rising scale plates being in normal or lower case position. Fig. 8 is a fragmentary view showing the relation of the scale plates to the carriage frame when the latter is at the limit of its movement to the right.

Referring to Fig. 7, type bars 1 having upper and lower case types, are mounted on a fulcrum rod 2 and actuated by key levers 3 connected through bell cranks 4 to the type-bars to cause the latter to swing upwardly and rearwardly against the front face of a roller platen 5. The platen is mounted on a shaft 6, journaled in a platen frame 7, shiftable on the carriage 8 to bring the platen to upper and lower case positions. The platen frame is shifted by means of shift keys 9, there being preferably a shift key at each end of the keyboard, on a shift key lever 10 fulcrumed at 11, and having an arm 12 extending upwardly to swing a platen shifting frame comprising blocks of wood 13 on a wood shaft 14 and carrying a shift key 15 on which rests a roller 16, on the platen frame. When a shift key 9 is depressed, the shift key 15 is moved upwardly and carries the platen vertically upward to upper-case position. The carriage is driven in letter-feed direction by the usual swing drum 17, connected through a belt 18 to the carriage, the latter running on a rear guide rail 19 and a front guide rail, not shown.

The letter-feed travel of the carriage is controlled by escapement mechanism con-

tributing an escapement wheel 20 driven by a pinion 21, running in mesh with a carriage rack 22. A key 23 pivoted at 24 is connected to the rack 22 for lifting said rack from the pinion 21 and permitting the carriage to run independently of the escapement mechanism. The rotation of the escapement wheel 20 is controlled by a dog rocker 25 carrying dogs 26 working with the wheel 20, said rocker being rocked by a universal bar 27, actuated by shoulders 28 on the type-bars. Each time a type-bar is swung to printing position, the universal bar 27 is moved rearwardly, and rocks said dogs 26 to permit rotation of the escapement wheel a distance of one tooth.

The parts thus far described may be of the usual construction found in Underwood typewriting machines.

Mounted on the type-bar segment 30 on opposite sides of the printing center are scale plates or wings 31 and 32, which may be of usual construction and may indicate the bottom edge of the writing line when the platen is in lower-case position. The scale markings 33 thereon at letter space intervals serve as a gage in adjusting the work-sheet laterally to register a letter space with the printing point. The wings 31 and 32 are adapted to swing toward and from the platen surface, being pivotally mounted by means of pintles 34 and brackets 35 on the type-bar segment 30. Coil-springs 36 urge said wings toward the platen.

In accordance with the present invention a pair of rising scale plates or wings 37, 38 are slidably mounted on the wings 31, 32, between the platen and said wings 31, 32 to permit the wings 37, 38 to move up and down with the platen during its case-shifting movements. The sliding connection is between the shifting and non-shifting wings may comprise guide-blocks 39 connected by screws 40 to the wings 37, 38, said blocks slidably in vertical slots 41 in the wings 31, 32.

The rising scale plates 37, 38 are normally held down by springs 42 assisted by gravity, each of which springs may be secured at one end to the segment 30 and at its other end to a block 43 fixed on the inner face of a rising scale plate. The rising scale plates may also be provided with scale gradations at letter-space intervals which may be held in place of the scale 33 when the platen is in upper-case position. The upper edge 44 of the plates 37, 38, coincides with the bottom edge of the line of writing (see Fig. 1).

The scale plates 37, 38 are supported and carried up and down with the platen by means of a supporting rod 45 extending in along the front of the platen and parallel therewith, said rod secured to a fixed part of the platen frame by means of arms 47 fixed to the rod 45 and clamped to blocks on the rod 46 by screws 48 extending through elong-

gated openings in said arms 47, this connection permitting adjustment of the rod 45 to accurately adjust the rising scale plates to the line of writing. The rod 45 enters 5 grooves 49 in the guide-blocks 43, said blocks sliding along the rod during the movement of the platen in the direction of its length and operating positively to lift the scale plates 37, 38 with the platen to the Fig. 1 10 position, when the platen is shifted to upper-case position. In other words, the shifting scale plates maintain a fixed relation to the platen during its case-shifting movements. It will thus be seen that the position of the 15 writing line is accurately located when the platen is in upper-case position as well as when in lower-case position.

As the scale plates shift with the platen, they are adapted to hold in position on the 20 platen the lower edge of a work-sheet that has been fed beyond the usual platen feed rolls, so that the writing may be carried very close to the bottom of the work-sheet. The scale plates prevent the work-sheet from 25 slipping or becoming displaced as the platen shifts up and down; the scale plates may also serve as card-holders for maintaining cards, envelopes, and the like in position on the platen.

30 In the machine illustrated, the rising scale plates 37, 38, if maintained in upper-case position, would interfere with the frame ends 50 of the carriage as the latter nears its limit of travel in either direction. In other words, the frame ends 50 (Fig. 1) extend 35 across the path of travel of the scale plates. The present invention provides means for automatically dropping each of said plates as it is approached by the carriage frame, so 40 that such interference is avoided without unduly shortening the scale plates.

To permit the scale plates to drop at the proper time, the supporting rod 45 terminates at such points that, as either scale 45 plate approaches the carriage frame, the corresponding guide-block 43 slides off said rod and permits the plate to be thrown down by its spring 42. To further assist in the release of the plate from the rod 45, cams 51 50 are located adjacent the ends of the rod. These cams may be secured to paper guiding extensions 53 of the paper shelf 54, and lie in the path of the guide-blocks 43, and operate positively to force the scale plates outward or away from the platen a sufficient 55 distance to release them from the supporting rod 45. Thus, in Fig. 2, the carriage is near the limit of its movement to the right, and the wing 37 has been moved into position to 60 be thrown outward from the platen by the cam 51, (see also Fig. 4), and thrown by its spring 42 to lower-case position in which it will not interfere with the carriage as the latter is moved to the limit of its travel to 65 the right.

In Fig. 5 the parts are shown in the position assumed just prior to the release of the wing 37 by the cam 51. As here shown, the cam has been brought up to the guide-block 43, and any further movement of the carriage 70 to the right will cause the cam to force said block 43 outward and release it from the supporting rod 45 and permit the wing to drop.

The right-hand wing 38 is released in like 75 manner as the carriage approaches the limit of its movement to the left. The cam plates 51 serve not only to release the wings 37, 38, and permit them to drop, but also hold said wings away from the platen, so that they 80 cannot catch on the lower edge of a work-sheet when the platen is shifted up and down while said edge of the work-sheet is close to the printing line. The cam plates 51 also serve to protect the usual front platen feed 85 rolls 55 from being rubbed by the wings 37, 38 during the travel of the carriage.

Variations may be resorted to within the scope of the invention, and portions of the improvements may be used without others. 90

Having thus described my invention, I claim:

1. In a typewriting machine, the combination with a platen shiftable to upper and lower case positions, of a line-gage extending along the face of the platen at the writing line, and means forming a running connection between the platen and gage for positively moving said gage both up and down with the platen as the latter is shifted, 95 100 and thereby indicating the writing line when the platen is in both upper and lower case positions.

2. In a typewriting machine, the combination with a roller platen shiftable to upper and lower case positions, of a work-piece holding gage mounted on the machine frame and bearing against the platen or a work-piece thereon along the line of writing, and means forming a running connection between the platen and gage permitting the gage to remain stationary during the letter-feed travel of the platen and positively shifting said gage both up and down with the platen, thereby maintaining a substantially constant relation of the gage to the platen during the case-shifting movements of the latter. 110 115

3. In a front-strike writing machine, the combination with a carriage and a roller platen mounted thereon and shiftable to upper and lower case positions, of wings mounted on the machine frame on opposite sides of the printing center and having their upper edges extending horizontally along the printing line on the platen, means to hold said wings with a yielding pressure against the platen at the printing line, and means on the carriage to shift said wings up and down with the platen and maintain the 120 125 130

relative position of the platen and said wings substantially unchanged as the platen is shifted to upper and lower case positions.

4. In a typewriting machine, the combination with a roller platen, of a set of type-bars having upper and lower case types, a support on which the type-bars are mounted to swing to and from the platen to cause the types to print, said platen and support relatively shiftable to enable the types of either case to print, said platen and support 10 relatively shiftable to enable the types of either case to print, a line-gage mounted on said support and extending along the printing line on the platen, and shifting means for said gage moving with the platen and having a positive running connection directly with the gage permitting the gage to remain stationary during the letter-feed travel of the platen, said shifting means operable positively to shift the gage relatively to its 15 support during the case-shifting movements to both case positions to maintain the gage in position to indicate the line of writing for both case positions.

5. In a typewriting machine, the combination with a platen frame and platen shiftable up and down to upper and lower case positions, of a line-gage extending along the face of the platen, means on the platen frame having a running connection with the line-gage to hold it at the writing line when the platen is in upper case position, and a spring to apply a downward pressure to said gage and coöperating with said means to move said gage downward into position to expose 30 to view the writing line when the platen is shifted downward to lower case position.

6. In a front-strike writing machine, the combination with a carriage and a roller platen mounted thereon and shiftable to upper and lower case positions, of a plate having its upper edge extending along the printing line on the platen, said plate mounted to swing on the machine frame to move its said edge toward and from the platen, and means to shift said plate up and down with the platen and positively prevent up or down movement of said plate relatively to the platen, to thereby maintain the relative position of the platen and said 45 plate substantially unchanged as the platen is shifted to upper and lower case positions, said plate being released from said shifting means when swung away from the platen to permit the platen to shift independently 50 of said plate.

7. The combination, with a roller platen having a letter-feed movement in a direction parallel with its axis, of types to print thereon, said types having a common printing center, a gage extending along the printing line and held stationary during the letter-feed travel of the platen, said platen shiftable to upper and lower case positions, and means moving with the platen during 60 its letter-feed travel and case shifting move- 65

ments and operable positively to move said gage with the platen as the latter is shifted to upper case position, and thereby maintain the gage in position to indicate the printing line when the platen is in upper case position. 70

8. In a typewriting machine, the combination with a carriage, of a platen thereon shiftable to upper and lower case positions, means forming a gage to indicate the position of the printing line when the platen is in upper case position, and a gage permanently in position to indicate the lower-case printing-line position. 75

9. The combination with a carriage and a roller platen mounted thereon and shiftable to upper and lower case positions, of a type-bar segment, type-bars mounted thereon to swing upwardly and rearwardly against the face of the platen or a work-piece thereon, wings mounted on said segment on opposite sides of the printing center to swing toward and from the face of the platen, means to hold said wings with a yielding pressure against the platen or work-piece thereon, and means to shift said wings up and down as the platen is shifted to upper and lower case positions and to lock the wings against either up or down movement relatively to the platen, and thereby maintain a substantially 90 constant relative position of said wings and the platen during the case-shifting movements of the platen. 95

10. In a typewriting machine, the combination with a roller platen shiftable to upper and lower case positions, of a type-bar segment, scale plates mounted on said segment on opposite sides of the printing center and arranged to swing toward and from the face of the platen, rising scale plates between said platen and said first-mentioned scale plates and slidably connected with the latter to move up and down with the platen as the latter is shifted, and means shiftable up and down with the platen to lift and rising scale plates with the platen to indicate the line of writing when the platen is in upper case position. 100 105

11. In a typewriting machine, the combination with a platen shiftable to upper and lower case positions, of a type-bar segment, a work-piece-holder, a swinging support on said segment, in which said holder is slidably mounted for movement up and down with the platen as the latter is shifted to the upper and lower case positions, said support arranged to swing said holder toward and from the face of the platen, and means for causing said holder to bear with a yielding pressure against a work-piece on the platen. 110 115

12. The combination with a carriage and a platen mounted thereon and shiftable to upper and lower case positions, of a work-piece holder in position to bear against the face of a work-piece on the platen substan- 120 125

- 5 tially along the printing line, and means carried with the platen to shift said holder up and down with the platen, said means having a sliding connection with the holder permitting the latter to remain at rest during the travel of the carriage and arranged to positively prevent the holder from shifting up or down relatively to the platen while the latter is in either case position.
- 10 13. In a typewriting machine, the combination with a carriage, of a platen frame and platen shiftable on the carriage to upper and lower case positions, a combined line-gage and work-holder extending along the face of the platen at the printing line, and a supporting rod on the platen frame extending in the direction of the letter-feed travel of the platen and having a sliding connection with said combined gage and work-holder permitting the latter to remain at rest during the letter-feed travel of the platen, said rod forming a means for shifting the combined gage and work-holder up and down with the platen when the latter is shifted to upper and lower case positions.
- 15 14. In a typewriting machine, the combination with a carriage, of a roller platen and platen frame shiftable on the carriage to upper and lower case positions, a pair of wings mounted on the machine frame on opposite sides of the printing center to swing to and from the face of the platen along the printing line, said wings free to shift with the platen to upper and lower case positions, and a supporting rod on the platen frame extending parallel with the platen axis and having a sliding connection with said wings in the direction of the letter-feed travel of the platen, and forming a positive means for shifting the wings with the platen to maintain the position of the wings on the platen unchanged as the platen is shifted to upper and lower case positions.
- 20 15. The combination with a carriage, of a platen frame and platen thereon shiftable to upper and lower case positions, a gage plate extending along the face of the platen in position to indicate the position of the line of writing, a supporting rod on the platen frame having a sliding connection with said gage plate to slide thereon in the direction of the letter-feed travel of the platen, said supporting rod forming a means to shift the gage plate up with the platen to indicate the writing line when the platen is in upper case position, and means forming an adjustable connection between said rod and the platen frame for adjusting said rod and gage plate up and down relatively to the platen to accurately position the gage plate with respect to the writing line.
- 25 16. In a typewriting machine, the combination with a carriage and a platen thereon having a case-shifting movement, of a traveling gage plate or work-piece holder extending along the face of the platen adjacent the printing line, and means for causing said plate or holder to shift with the platen when the platen is shifted while the carriage is in an intermediate position, said means being ineffective to shift said gage or holder with the platen when the carriage is near the limit of its travel.
- 30 17. The combination with a carriage and a platen shiftable up and down thereon to upper and lower case positions, of a gage plate extending along the face of the platen at the printing line and reaching beyond the end of the carriage frame when the carriage is at the limit of its travel, means for restraining said gage plate from moving with the platen in letter-feed direction, and means for causing the gage plate to shift up and down with the platen while the carriage is in an intermediate position during its travel, said means being ineffective to shift the gage plate upward when the carriage is near the end of its travel, thereby preventing interference between the carriage frame and the gage plate.
- 35 18. In a typewriting machine, the combination with a carriage and a platen shiftable up and down thereon, of a gage or work-piece-holder extending along the face of the platen at or near the printing line and reaching beyond the end of the carriage frame when the carriage is at one limit of its travel, means to shift said gage or holder up and down with the platen while the carriage is in an intermediate position, and means to prevent said gage or holder from rising with the platen while the carriage is near said limit of its travel, thereby preventing interference between the said gage or holder and the carriage frame.
- 40 19. In a typewriting machine, the combination with a carriage and a platen mounted to shift thereon to upper and lower case positions, of wings or plates mounted on opposite sides of the printing center and restrained from movement in the direction of the carriage travel, said wings extending along the face of the platen adjacent the printing line, means for shifting said wings up and down with the platen as the latter is shifted to upper and lower case positions while the carriage is at an intermediate point in its travel, each wing being released from said shifting means when the corresponding end of the carriage frame approaches said wing, and means to hold the wings down when thus released, whereby each wing is maintained in its lowered position irrespective of the case-shifting movement of the platen when the end of the carriage frame is adjacent said wing, thereby enabling said wings to be made of greater length without interference with the carriage frame, than would be permitted if

said wings were shiftable up and down with the platen throughout the entire range of travel of the carriage.

20. In a typewriting machine, the combination with a carriage and a platen thereon shiftable to upper and lower case positions, of a gage or work-piece-holder extending along the printing line on the platen and arranged to swing to and from the platen, and a rod carried with the platen and shiftable up and down therewith, said rod moving along said gage or holder during the travel of the carriage and forming a means for shifting said gage or holder with the platen to upper and lower case positions, said rod terminating at a point to release the gage or holder as the carriage approaches the end of its travel and thereby prevent the gage or holder from being shifted with the platen when in such position that it would interfere with the carriage frame.

21. In a typewriting machine, the combination with a carriage and a platen thereon shiftable to upper and lower case positions, of a gage or work-piece-holder extending along the printing line on the platen and arranged to swing to and from the platen, a rod carried with the platen and shiftable up and down therewith, said rod moving along said gage or holder during the travel of the carriage and forming a means for shifting said gage or holder with the platen to upper and lower case positions, said rod terminating at a point to release the gage or holder as the carriage approaches the end of its travel and thereby prevent the gage or holder from being shifted with the platen when in such position that it would interfere with the carriage frame, and a cam in position to throw the said gage or holder off said rod and hold it away from the platen while the carriage is near the limit of its travel.

22. In a typewriting machine, the combination with a carriage, of a platen frame and platen shiftable to upper and lower case positions on the carriage, wings mounted on opposite sides of the printing center to swing toward and from the face of the platen, a rod on the platen frame extending parallel with the platen and having a sliding connection with said wings, said rod forming a means to shift said wings up and down with the platen, cams carried with the carriage in position to engage said wings and release each wing from said rod when the adjacent end of the carriage frame approaches said wing, and means for holding each wing in its lowered position when released from said rod, thereby preventing interference between said wing and the carriage frame when the platen is shifted.

23. In a typewriting machine, the combination with a carriage and a platen there-

on shiftable to upper and lower case positions, of non-traveling wings on opposite sides of the printing center and extending along the face of the platen, means for shifting said wings up and down with the platen while the carriage is in intermediate positions, and means to automatically release each wing from its shifting means when the corresponding end of the carriage approaches said wing, thereby preventing the wing from shifting with the platen, each wing being operative by its shifting means to move up and down with the platen when the other wing is inoperative, so that one or both of said wings will always move with the platen when the latter is shifted.

24. In a typewriting machine, the combination with a carriage and a platen shiftable up and down thereon, of a line gage extending along the face of the platen at the printing line, a support on which said gage is mounted, means to shift said gage up and down on said support with the platen to upper and lower case positions, said support mounted on a stationary part of the machine to swing about an axis parallel with the platen and thereby permit the gage to swing toward and from the platen, and a spring arranged to apply pressure to said support in a direction to hold the gage against the platen.

25. In a typewriting machine, the combination with a carriage and a platen shiftable up and down thereon to different case positions, of a combined gage and work-piece holder extending along the face of the platen at or adjacent to the printing line, a support on which the gage is mounted to shift up and down, means for causing said gage to shift up and down with the platen to maintain the gage at the printing line while the platen is in either case position, a type-bar frame on which said support is pivotally mounted to swing toward and from the platen, and a spring tending to swing said support toward the platen, and thereby holding the gage with a yielding pressure against the platen.

26. In a typewriting machine, the combination with a carriage and a platen thereon shiftable to upper and lower case positions, of a gage or work-piece holder extending along the printing line on the platen and arranged to swing toward and from the platen, and a rod carried with the platen and shiftable up and down therewith, said rod moving along said gage or holder during the travel of the carriage and forming a means for shifting said gage or holder with the platen to upper and lower case positions, said gage being automatically released from said rod when the carriage reaches a predetermined position in its travel.

27. In a typewriting machine, the combi-

nation with a carriage, a platen frame, and a platen shiftable thereon to upper and lower case positions, of wings mounted at opposite sides of the printing center to swing toward and from the face of the platen, a rod on the platen frame extending parallel with the platen and having a sliding connection with said wings, said rod forming a means to shift the wings up and down with the

platen, and cams carried with the carriage 15 in position to engage said wings and release each wing from said rod when the adjacent end of the carriage frame approaches said wing.

FRANK L. MORGAN.
